UNITED STATES PATENT OFFICE.

LEWIS E. MCKOWN AND JOHN FUCHS, OF BRIMFIELD, ILLINOIS.

AUXILIARY-LOCKING MECHANISM FOR SAFES.

Application filed January 26, 1924. Serial No. 688,858.

To all whom it may concern:

Be it known that we, LEWIS E. MCKOWN and JOHN FUCHS, both citizens of the United States, residing at Brimfield, in the 5 county of Peoria and State of Illinois, have invented new and useful Improvements in Auxiliary-Locking Mechanism for Safes; and we do hereby declare that the following is a full, clear, and exact description of the 10 invention, which will enable others skilled in the art to which it appertains to make and use the same.

This invention pertains to improvements in safes, relating more particularly to an 15 auxiliary locking means therefor, or in addition to the usual combination lock usually fitted to the safe.

An object of the invention is to provide 20 mechanism which, when the usual safe combination lock is tampered with, or knocked off, will automatically be released to engage and prevent the locking-bolt mechanism from being operated thus thwarting an attempt to gain entrance to the safe.

25 Another object is that of providing a mechanism for automatically engaging the locking-bolt mechanism when the safe is tampered with, but which can be retracted from outside the safe by persons familiar 30 with the method of so doing, thereby permitting the safe to be opened.

Another object is to furnish a mechanism 35 for the purposes named that can be adjusted to various positions so that no one safe provided therewith will be like another with respect to the position of such mechanism.

To the end that the invention may be 40 thoroughly understood, the accompanying drawing is made a part hereof, and wherein,

Figure 1 is an elevation of the inner side 45 of a safe door showing the invention in place thereon.

Figure 2 is a vertical section of part of a safe door, on line 2—2, Figure 1, showing 50 certain parts of the invention, and

Figure 3 is a horizontal section of part of a safe door showing parts of the invention 55 in place thereon.

The safe door is denoted by the character 60 1 and in Figure 1 is viewed at its inner side, 2 indicating the usual locking-bolts extending from one edge of the door to enter holes in the jamb, not shown, while 3 is a bar to which the bolts are secured. Any 65 usual combination lock is shown at 4 to receive an extension 5 secured on the said bar

3, to none of which, however, any claim to novelty is attached since commonly used. At 6 is a box adapted to be placed upon the inner wall of the door 1 to contain cer- 60 tain mechanism now to be described as being involved in the present invention. Said box, which, however, may merely be a plate, if desired, may be secured in position on the door by any suitable means, but pref- 65 erably it is made adjustable in position. That is to say, 7 designates two screws let through and seated in one of the edges of the door and threaded into the wall of the said box 6 so that by turning them the lat- 70 ter may be shifted in position for a purpose to be made known later. Truss rods 8 may be let through opposite edges of the door and be made to overlie the box holding it firmly against the door by friction and may 75 pass through eyes 9 on said box, if desired, there being turn-buckles 10 for adjusting said rods for tension.

Pivoted at 11 within the box is a trigger 80 consisting, for example, of a depending member 12 having a laterally extending lug at its lower end adapted to engage and support a similarly formed member 14 as part of a lock-lever 15 pivoted on the box at 16, for example. A spring 17 attached at its 85 ends to the trigger 12 and some part of the box 6 tends to draw the said trigger away from the member 14, while a spring 18 attached at its ends to the locking-lever 15 and the box serves to positively draw said 90 lever away from the said trigger.

On a center pin or staff 19 of the combination lock 4 is loosely placed a bar 20 whose lower end is also loosely placed upon a post 21 extending from the door, Figure 95 2, whereby said bar is held from movement in a lateral direction as viewed in Figure 1. A wire or cable 22 is attached to the other or free end of the bar and may pass over a pulley 23, for example, if desired, and ex- 100 tends toward and has connection with the trigger 12.

Secured to the bar 3 carrying the bolts 2 is a bar 24 extending toward and into the box 6 and having a recess 25 in its end. 105 Said recess is adapted to receive into it the locking-lever 15, see dotted lines in Figure 1, and forms a stop therefor as against the pull of the spring 18 and as a stop for the said bar 24 in an attempted movement to 110 unseat the bolts 2.

In use the parts are set as shown in Fig-

ures 1 and 2 whether the safe is open or closed and remains normally in those positions, or with the lever 15 suspended from the trigger and free of the said bar 24, the 5 wire or cable 22 and the bar 20 holding the trigger from movement it would otherwise have due to the spring 17.

The combination lock may be operated and the safe used in the usual manner without disturbing the mechanism of the invention in any way. When, however, an attempt is made to break into the safe by knocking off the combination lock as must be done in order to free the locking bolt 15 mechanism, that act, or any act unusual to the conventional manner of opening a safe will result in jarring off or unseating the bar 20 whereupon the spring 17 will, when thus released, remove the trigger 12 from 20 engagement with the locking-lever 15. The spring 18 is thereupon free to operate the said lever 15 drawing it into the recess 25 of the bar 24 effectively preventing said bar being moved to unseat the bolts 2, and explosives must then be required if the safe is to be entered. However, the owner may readily be permitted to unseat the bolts 2 by a method now to be described. As shown in Figure 3, the pivot 16 for the locking-lever 15 is provided with a slotted end 16', for example, which lies adjacent to the surface of the door as shown in the present instance, and after the installation of the mechanism it is only necessary to obtain the 35 measurements from two of the edges of the door to the center of the pivot 16 so that when necessary to permit the unseating of said bolts 2 after having been locked in the manner described, a hole may be drilled 40 through the door, for instance at the point X in said Figure 3, so that a suitable tool may be inserted to engage the said pivot. A slight turn will lift the lever 15 against the pull of the spring 18, thus lifting said 45 lever from the bar 24, whereupon the locking-bolt mechanism may be readily operated. Upon opening the door the engagement of the trigger 12 and the lever 15 may be made so that the device is then ready 50 for a succeeding operation after restoring the combination lock parts.

The box 6 is made adjustable in position, it may be seen, so that no one after having aided the owner in drilling operations may 55 afterwards know just where a new hole is to be made, the hole previously made having been filled and the position thereof made invisible. By loosening the turn-buckles 10 a considerable degree of movement of the box is possible by means of 60 said screws 7 as may be understood, the wire or cable 22 being adjusted in length to accommodate it to any changes made. However, other methods of securing the box in 65 place and for adjusting it may be employed

as is evident, since the method described is but one of the ways of accomplishment of the object.

What is claimed is:

1. In a device of the nature described, in combination with a safe door, its locking bolt mechanism, and combination lock, a lock carrying body movable over the inner face of said door to adjusted fixed positions, a locking lever pivotally mounted thereon adapted to be moved into the path of movement of part of the locking bolt mechanism, means also mounted on the body for positively causing such movement of the lever, a trigger pivoted on the body engaging the lever adapted for maintaining said trigger in its disengaged position, means on the body connected to the trigger to positively operate it for releasing the lever, and means connected to the trigger to hold it in engagement with the said lever and adapted when the combination lock is affected to release said trigger and permit its withdrawal from the lever. 70 75 80 85

2. In a device of the nature described, in combination with a safe door, its locking mechanism, and combination lock, a lock carrying body movable over the inner face of said door to adjusted fixed positions, a locking lever pivotally mounted on the body adapted to be moved into the path of movement of part of the said locking mechanism, means on the body for positively causing movement of the lever, a trigger pivoted on said body engaging the lever adapted for maintaining it in its disengaged position, means connected to the trigger to positively operate it for releasing the lever, and means connected to the trigger to hold the latter in engagement with the lever and adapted 90 95 100 when the combination lock is affected to release the trigger and permit its positive withdrawal from the lever. 105

3. In combination with a safe door, its locking bolts, and combination lock, a mounting shiftable relatively to the door, means connected with the mounting for positively shifting it and for securing it in fixed adjustment, and mechanism carried wholly by the mounting including a lever adapted to engage and prevent the locking bolts from being unseated from the jamb of the safe and a trigger to engage it, and an operating part connecting the combination lock and said mechanism. 110 115

4. In combination with a safe door, a lock carrying body, means to hold the same frictionally upon the inner surface of said door, and means to shift the body upon the door and for securing it in permanent adjustment. 120 125

5. In combination with a safe door and a locking-bolt mechanism, a lock carrying body, means to hold the same frictionally against the inner surface of the door, a 130

pivotaly mounted locking-lever adapted to enter the path of part of the locking-bolt mechanism, the pivot portion of the same having an end adjacent said door surface
5 engageable by a tool whereby said lever may be moved out of said path, a pivoted trigger adapted to engage and hold the lever out of said path, elastic means engaging the trigger constantly tending to move the trigger and release the lever, releasable means
10 to hold the trigger in the lever engaging

position in opposition to the said elastic means, and means to shift the lock-carrying body upon the door and for maintaining it in a fixed position. 15

In testimony whereof we affix our signatures in presence of two witnesses.
